UNITED STATES PATENT OFFICE

PERCIVAL S. TICE, OF CHICAGO, ILLINOIS

CARBURETOR

Application filed December 18, 1924. Serial No. 756,628.

The purpose of this invention is to provide an improved form and construction of a carburetor for internal combustion engines, adapted to automatically suit the fuel mixture to varying engine speeds and loads, and also automatically afford quick acceleration; and with these functional improvements to be economical of construction and convenient for installation.

10 In the drawings:

Figure 1 is a plan view of a carburetor embodying this invention.

Figure 2 is a partly sectional side elevation of the same section being made axially 15 of the fuel mixture conduit through a part of its extent.

Figure 3 is a section at the line 3—3 on Figure 1.

Figure 4 is a section at the line 4—4 on 20 Figure 2.

Figure 5 is a detail section in the plane of the lines 5—5 on Figure 1 and 5^a—5^a on Figure 4.

Figure 6 is a detail section at the plane of 25 the lines 6—6 on Figure 2 and 6—6 on Figure 5, intersecting at the point 6^x on Figure 5.

The structure shown in the drawings comprises the following parts formed as an integral casting, viz: First, the fuel mixture 30 conduit, 10, designed to extend horizontally when in service, having a constriction at 11 giving its cavity Venturi form; second, the float bowl or level-governing chamber, 12, extending vertically transversely of the fuel mixture conduit laterally thereof, opposite 35 the constricted Venturi portion, and third, a nexus, 15, between the fuel mixture conduit and the float bowl, which nexus affords passage and mounting for the needle valve hereinafter mentioned. The float bowl, 14, is 40 provided with a removable cover, 16, having a boss, 17, in which are formed the fuel inlet passages, 18 and 18^a, and the air-vent passage, 19. The fuel inlet passage has a seat, 20, at 45 its inner end for the valve, 21, controlled by the float, 22; and at the outer end of said inlet passage there is screwed thereinto a nipple, 24, for connecting a fuel supply pipe, lead- 50 ing from the fuel source (not shown) for

supplying the float bowl by any preferred method.

The liquid fuel duct from the float bowl comprises the outlet passage, 26, from said bowl, and the discharge into the fuel mixture conduit seen at 27, entering said conduit substantially at the Venturi constriction, 11.

The outlet passage, 26, from the float bowl is formed by drilling across the nexus, 15, near the lower end thereof into the lower part of

the bowl, the outer end of the bore being permanently closed by a plug, 28. The discharge passage, 27, into the venturi is formed by drilling from the opposite side of the venturi, the bore through said opposite side being permanently closed by a plug, 29. Between the outlet, 26, from the bowl and the discharge passage, 27, into the venturi of the fuel mixture conduit, the fuel duct comprises

a trap chamber, 30, formed in the nexus, 15, through which trap chamber the needle valve, 31, extends from the upper end of said nexus. This trap chamber and the seat and guide bearing for the needle valve are formed by

first boring the nexus from the upper end through to the bottom in a line causing said bore to intersect the discharge passage, 27, counterboring at the lower end to form the trap, 30, and further counterboring the

lower part of the first mentioned counterbore 80 in two diameters and threading the last counterbore at the upper end portion for receiving a plug, 35, threaded at its upper end for screwing into the threaded counterbore, and having an exterior shoulder at its lower

end for stopping and seating liquid-tight at the lower end of the nexus. Said plug has an annular groove, 36, a cross bore, 37, at that

groove and an axial bore, 38, from the upper end of the plug into said cross bore, constituting the connection for fuel flow from the outlet, 26, into the lower end of the trap chamber, 30. Before inserting the plug, 35,

there is inserted through the trap chamber 85 and made fast at its upper end in the lower end of the original first mentioned bore which is counterbored to form the trap chamber, below the intersection of said bore with the duct, 27, a sleeve, 39, which when thus made fast

90 95 99 100

at its upper end terminates at its lower end a short distance above the plug, 35. This sleeve, it will be seen, renders the chamber, 30, a trap as above designated, in which 5 under certain conditions the liquid fuel will be accumulated as hereinafter described. The original bore in the upper part of the nexus leading out from the top of the trap chamber is counterbored from the upper end 10 to receive a stuffing box, 43, and is threaded below said counterbore to engage the stem, 44, of the needle valve, 31, which, below the threaded part of said stem, is reduced in diameter for extending through the sleeve, 39, 15 loosely enough to permit free liquid flow around it through the sleeve, and at its lower end is suitably tapered for seating at the upper end of the axial bore 38, of the plug, 35. From the upper end of the trap chamber, 20 30, a duct, 45, is bored leading into the upper part of the float bowl, above the liquid level thereof, for admitting atmospheric pressure at all times to the trap, 30.

A posterior throttle valve, 50, is positioned 25 a short distance beyond the Venturi constriction, 11, and has its stem, 51, provided outside the fuel mixture conduit with an operating lever, 52, and the usual operating connections (not shown), an abutment, 53, being provided for encounter of a lug, 54, projecting from the hub of the lever, 52, for stopping the valve at wide open position, the lever having also an adjustable abutment in the form of a stop screw, 55, set through a lug, 56, for 30 encounter with the abutment, 53, at the desired limit of closing movement, determined by the adjustment of said screw. An anterior throttle is indicated at 60 with the usual operating means and connection for the customary function of such anterior throttle.

An important characteristic and feature of this type of carburetor is the provision of 45 sub-atmospheric pressure connection from a point beyond the posterior throttle valve to the liquid fuel source or path of delivery; whereby, under certain conditions the fuel may be drawn directly into the manifold by-passing both the throttle valve and the mixing chamber of the carburetor; and for this 50 purpose a bore, 70, is made from the inner end of the unitary casting extending in the general direction of the slope of the discharge element of the Venturi passage, to a point of intersection with a second bore, 71, 55 directed in from the lower side of the casting opposite the constriction, 11, of the Venturi passage, said bore, 71, reaching and connecting with the fuel discharge passage, 27. The outer ends of the bores, 70 and 71, are 60 closed by plug, 70^a, and a valve, 71^a, respectively, and a bore, 72, is made from the inner side of the conduit at a point just beyond the seating position of the posterior throttle valve, into the bore, 70, whereby it will be 65 understood there is afforded a pressure com-

munication between the fuel path leading for discharge of liquid fuel into the venturi, and the region beyond the closed throttle, which when the engine is running, however idly, is a region of sub-atmospheric pressure. The valve, 71^a, serves to regulate at will the freedom of communication between the fuel passage from the float bowl and the duct, 70.

It will be understood that the provision described for connecting with a source of sub-atmospheric pressure the path of flow of the liquid fuel from the level-governing chamber or float bowl to the fuel mixture conduit at the Venturi constriction, serves the purpose of causing liquid fuel to be drawn directly from said path into the engine intake beyond the throttle valve when the latter is closed, or at position for idling of the engine; and that under these conditions also there may be admixture of air with the fuel drawn in from the Venturi constriction through the passage, 27, reversing the direction of flow through that passage, from that which occurs when the posterior throttle is open with the engine running at high speed, causing inflow 90 of air at high velocity through the venturi, and consequent low pressure at the discharge of the passage, 27, into the venturi; For understanding the function of this passage under idling conditions it should be borne in mind that when air is drawn through a well-formed Venturi throat or constriction in a passage, there is induced in the throat a reduction of pressure, that is proportional to the square of the velocity of flow of the air. Since liquid discharges from a jet with the velocity proportioned to the square root of the pressure difference applied to it, it will be seen that the velocity of liquid flow from a jet discharging into a throat as in a carburetor, would naturally, in the absence of preventing reasons, at all times be directly as velocity of air flow through the throat, thus giving a constant mixture proportion.

This would be the result if it were not for the fact that to prevent flooding when the engine is not running, the standing level of the fuel must be a little distance below the point at which the fuel is to be discharged from the nozzle or jet port, necessitating a slight lift of the liquid to bring it to the discharge point, and for the further fact that a measurable force is required to overcome the surface tension or capillary contraction existing between the liquid and the terminal surface of its discharge passage which may properly be thought of as adhesion between the liquid and the metal. These causes operating to prevent the movement of the liquid in accordance with the law stated are constants, while the pressure reduction varies as the square of the velocity flow and the liquid discharge varies with the square root of the pressure difference. It will be seen, therefore, that the interference with the proper 100 105 110 115 120 125 130

proportions of the mixture due to the constants, and which may be taken into account and compensated by proportioning the passages to produce proper mixture at any selected air flow velocity, will operate to defeat the proper proportions at any materially lower velocity than that for which the passages are proportioned. While, with the passages properly designed as to form and dimensions, the head acting upon the fuel by virtue of the air flow, may be at all times of exactly the right value to maintain constancy of mixture proportions; the effective head as represented by the actual fuel discharge, would be less than this applied head by an amount equal to the sum of a head equivalent to the surface tension or adhesive force mentioned, plus the negative head due to the slightly lowered standing level of the liquid (the governed level of the float bowl). And since the effect of this adhesive force is small when the applied head is large, and is large when the applied head is small, it will be seen the resistance to the liquid flow due to these constants, represents an increasingly great proportion of the total as the applied head decreases.

In the present construction this defect is overcome by the adjustable by-pass communicating with the fuel discharge passage immediately at its discharge end. By virtue of the pressure drop across this passage when the air flow through the Venturi throat is small, and the disturbance above described is maximum, the effective head can be maintained at suitable value to preserve the desired mixture proportions. Tests demonstrate that with this arrangement the idling by-pass so-called, operates solely as an avenue for the removal of the liquid brought to its entrance by the pressure drop or head created in the Venturi throat by the flow of the main column of air through the venturi; and that the pressure drop or head existing at the opposite end of the fuel discharge passage is not changed, being neither increased nor reduced, as a result of providing the by-pass and means for adjusting it as to flow capacity.

These results are obtained much more effectively in such a construction as described than when a separate jet or fuel passage is made to supply sufficient fuel to maintain the idling mixture; for the reason that in the construction herein shown, the variation is continuous and without breaks when the desired adjustment is one involving change in the mixture proportion with change in the air flow; whereas when a main supply jet and separate idling jet are employed, the idling jet alone discharges fuel at the smallest air flow, while the main jet discharges nothing; and at the largest air flow only the main jet discharges fuel, and the idling jet discharges nothing. Between these two sets of conditions there is a transition which always re-

sults in irregularities of the mixture proportions and usually is sufficient to be evidenced by irregular running of the engine, particularly if the carburetor adjustment has been made with a view to small fuel consumption. Such variations are not observable in the construction herein shown.

It will be understood also, that, normally the liquid fuel will stand in the fuel passage leading from the float bowl to the fuel mixture conduit at the level governed by the float in the float bowl, and that therefore, normally, the trap chamber, 30, will be full of liquid. And it may be seen that the flow-restricting plug, 35, commonly called a "metering" plug, by means of its retardment of the flow of the fuel in response to the engine suction, has the function of causing that upon sudden substantial increase of suction,—such as results from increasing the opening of the posterior throttle valve or closing the anterior throttle, the increased suction will withdraw the fuel from the trap faster than it can flow in through the restricted aperture, 38; and thereby the quantity of fuel contained in the trap will be added to the normal supply arriving through the metering plug, with the result of momentarily enriching the fuel mixture supplied to the engine, and causing quick acceleration of the engine. This is an important purpose of providing the fuel trap in the fuel passage from the float bowl, and the metering or flow-restricting means therein anterior to the trap.

Upon consideration of the structure above described, it will be seen that it performs the functions which characterize this type of carburetor by means very simple and economical of construction and easy of installation.

I claim:

1. A fuel mixture forming and supplying device for internal combustion engines and the like, comprising a fuel mixture conduit having an air inlet, and adapted to be connected for discharge at the engine intake, said conduit having in its course a fluid-flow accelerating constriction; a level-governing chamber constituting the immediate liquid fuel source; a throttle valve in the fuel mixture conduit between the fluid-flow accelerating constriction and the engine intake; a fuel passage from the liquid level governing chamber constituting the sole conduit for fuel from said chamber to the fuel mixture conduit anterior to the throttle valve, and discharging therein proximate to the fluid flow accelerating constriction; a trap in the course of said sole liquid conduit open at its upper end to atmospheric pressure, and having both the inlet from the level-governing chamber and the outlet toward the fuel mixture conduit at the lower part, and a branch liquid passage leading off from said sole conduit at a point in the latter be-

yond the trap, and at which said sole conduit is exposed to the air pressure in the fuel mixture conduit anterior to the throttle valve.

2. In the construction defined in claim 5 1 a fuel flow restricting means interposed in the liquid passage from the level-governing chamber anterior to the trap in said passage, and a manually operated valve co-operating with said flow-restricting means for regulating at will the degree of the restriction.

3. In the construction defined in claim 1 foregoing the trap being situated as to its entire liquid trapping cavity below the governed level of the level-governing chamber, 15 and a fuel flow restricting means interposed anterior to the entrance to the trap in the sole conduit from the liquid level-governing chamber to the fuel mixture conduit.

4. In the construction defined in claim 1 20 the level-governing chamber and the portion of the fuel mixture conduit comprising the flow accelerating constriction being a unitary casting, the trap chamber being in a neck of the casting connecting the level-governing chamber and the mixture conduit, 25 and having a flow-restricting metering obstruction at the bottom, forming the entrance port at the trap, and a needle valve seated in said port, having its stem extending up 30 through the entire vertical extent of the trap chamber, and emerging from the top thereof for exterior operation.

5. In the construction defined in claim 1 35 the level-governing chamber and the portion of the fuel mixture conduit comprising the flow accelerating constriction, being a unitary casting, the fuel mixture conduit being horizontal, and the level-governing chamber being positioned adjacent to the constricted portion of said conduit, the axis of 40 the horizontal conduit being substantially at the governed liquid level of said chamber, the trap chamber being formed in the neck of the casting connecting the level-governing 45 chamber and the mixture conduit, and having the flow-restricting means at the bottom, and forming the entrance port to the trap chamber; and a needle valve seated at said port and having its stem extending up from its 50 seat through the entire vertical extent of the trap, emerging from the upper side of said neck for exterior operation.

6. A fuel mixture forming and supplying device for internal combustion engines comprising a fuel mixture conduit forming an air inlet and adapted to be connected for discharge of fuel mixture at the engine intake; a level governing chamber constituting the immediate liquid fuel source, a throttle 60 valve in the fuel mixture conduit; a fuel passage constituting the sole conduit for fuel from the level governing chamber to the fuel mixture conduit anterior to the throttle valve; a liquid-flow-restricting means interposed in said sole conduit anterior its dis-

charge in the fuel mixture conduit, a trap located in the course of said sole conduit subsequent to the liquid-flow-restricting means, said trap being open at the upper part to atmospheric pressure and having both its inlet from the level governing chamber and its outlet to the fuel mixture conduit located at the lower part of the trap; and a branch liquid discharge passage leading off from the said sole conduit beyond the trap 70 and discharging in the fuel mixture conduit 75 beyond the throttle valve.

In testimony whereof, I have hereunto set my hand at Chicago, Illinois, this 15th day of December, 1924.

PERCIVAL S. TICE.
